(57) CLAIM

The ornamental design for a combined matress, pillow and sleeping bag, as shown.

DESCRIPTION

FIG. 1 is a top right perspective view of the combined matress, pillow and sleeping bag, as disclosed herein.
